UNITED STATES PATENT OFFICE

2,290,467

STOVEPIPE CLEANER OR SCRAPER

John Fleming, Dundee, Quebec, Canada

Application December 11, 1939, Serial No. 308,702
In Canada June 2, 1939

3 Claims. (Cl. 15—162)

This invention relates to stove pipe cleaners or scrapers.

It is well known that the interior of stove pipes become coated with soot after continued use. Various methods and devices have been employed to remove this soot. A common method has been to simply tap the outside of the stove pipe with a stick or similar article. However, this procedure removes only the loose soot and will not remove the soot that has become firmly attached to the interior wall of the stove pipe. Furthermore, this tapping tends to disfigure the exterior of the stove pipe.

Then again it has been customary to clean the interior of stove pipes with an old broom, a stick with a rag wound around it, etc. However, these methods have proven inefficient in that they take considerable time and even then a thorough cleaning is not obtained.

Accordingly, it is the main object of the present invention to provide a stove pipe cleaner or scraper which will remove the soot from the interior walls of stove pipes in a more efficient manner and in much less time than those used heretofore.

It is also an object of the present invention to provide a stove pipe cleaner or scraper which may be adjusted laterally to fit stove pipes of different diameters.

It is a further object of the present invention to provide a stove pipe cleaner or scraper wherein means is provided for taking up the wear of the cleaning bristles which may become bent or worn after continued use.

It is also an object of the present invention to provide a stove pipe cleaner or scraper wherein means is provided for increasing the pressure of the cleaning bristles against the interior wall of the stove pipe when the soot coating is particularly difficult to remove.

It is also an object of the present invention to provide a stove pipe cleaner or scraper which will remove the soot from stove pipe elbows as well as the body of the stove pipes generally.

Further objects and advantages of the present invention will be apparent upon reference to the accompanying drawing in which,

Figure 1 is a part sectional elevation of the preferred form of stove pipe cleaner or scraper as covered by the present invention.

Figure 2 is a sectional view taken on the line 2—2 of Figure 1.

Referring more closely to the drawing the stove pipe cleaner or scraper comprises the handle 10 on both sides of which are positioned similarly shaped brush members 11. These brush mem-

bers are composed of rigid backings of any suitable material, preferably wood, in which bristles 12, preferably wire, are anchored. At the outer end of the device the brush members are curved towards each other as indicated by reference numeral 13. The bristles 12 are anchored in the backings 11 throughout the length thereof as indicated in outline.

Passing through the handle 10 and connected thereto by pins 14 are a plurality of threaded bolt members 15, preferably two. Riding in screw threaded relation on these bolt members are the thumb engaging nuts 16. One of these nuts is placed on each side of the handle and is adapted to run the full length of the bolt member 15 positioned on that side of the handle. Attached to the brush members 11 are a plurality of support members 17 which preferably take the form of metallic sleeves, said sleeves being adapted to enclose the threaded bolt members 15. These sleeves are attached at one end to the brush members as at 18. Closely adjacent to the opposite end they project outwardly as at 19 to enclose the thumb engaging nuts 16. 25 These latter ends of the sleeves are not attached to the handle 10 in any way. The flanges 19 enclosing the thumb engaging nuts 16 are cut away as at 20 whereby the nuts may be engaged by the thumb of the user.

With this construction the brush members may be adjusted laterally to any desired position by simply turning the nut members 16 with the thumb. The nut members 16 will run along the bolts 15 and will carry the sleeves 17 with them. The brush members being attached to the sleeves 17 will move laterally and may be adjusted to any desired position as shown in dotted outline. Slots 21 are cut in the backings 11 so that the bolt members 15 may ride therein when the stove pipe cleaner or scraper is adjusted to its minimum size. The smallest size of the device is shown in the drawing. The handle is of a suitable length preferably 30 to 36 inches, and is provided with a crosspiece or handle 22 on the end thereof.

45 From the above description it is apparent that the stove pipe cleaner or scraper as covered by the present application may be adjusted laterally to fit stove pipes of different diameters by simply turning the nuts 16. Furthermore, should the bristles 12 become bent or worn through continued use they may be taken up by simply turning the nuts 16.

Then again when the soot coating is particularly difficult to remove the pressure of the bristles 12 against the interior wall of the stove pipe

may be increased by simply turning the nuts 16. The rounded end portions 13 provide a stove pipe cleaner or scraper which will remove soot from stove pipe elbows as well as the body of the stove pipes generally.

I claim:

1. A stove pipe cleaner or scraper comprising a handle, brush members disposed on each side of said handle, a plurality of threaded members attached to said handle and extending radially of said handle toward said brush members, thumb engaging nut members adapted to ride on said threaded members, support members attached to said brush members and adapted to engage said nut members, whereby said brush members may be adjusted laterally by simply turning said nut members.

2. A stove pipe cleaner or scraper as claimed in claim 1 wherein said support members comprise metallic sleeves adapted to enclose said threaded members and being movable relative thereto, one end of said sleeves being attached to said brush members, the opposite end of said

sleeves being enlarged to partially enclose said nut members.

3. A stove pipe cleaner or scraper comprising a handle, brush members disposed on each side 5 of said handle and being curved towards each other at one end, said brush members comprising substantially rigid backings in which a plurality of bristles are anchored, a plurality of threaded members passing through and attached to said handle, thumb engaging nut members adapted to ride on said threaded members, metallic sleeves attached to said backings and adapted to enclose said threaded members and being movable relative thereto, one end of said sleeves being enlarged 10 to partially enclose said nut members, whereby said brush members may be adjusted laterally by simply turning said nut members, slots being provided in said backings adjacent to said sleeves to receive the end of said threaded members when the stove pipe cleaner or scraper is adjusted to its minimum size.

JOHN FLEMING.
